UNITED STATES PATENT OFFICE.

CHARLES A. GOOZEY, OF PROVIDENCE, RHODE ISLAND, ASSIGNOR TO B. A. BALLOU & COMPANY INC., OF PROVIDENCE, RHODE ISLAND, A CORPORATION OF RHODE ISLAND.

SAFETY-CATCH.

1,321,621.

Specification of Letters Patent.

Patented Nov. 11, 1919.

Application filed June 9, 1917. Serial No. 173,749.

To all whom it may concern:

Be it known that I, CHARLES A. GOOZEY, a citizen of the United States, and resident of the city of Providence, in the county of Providence and State of Rhode Island, have invented certain new and useful Improvements in Safety-Catches, of which the following is a specification.

This invention relates to improvements in safety catches used on pins, brooches and the like, and has for its object to provide a catch of this character designed more especially for use on very small articles of jewelry; and to provide a lock member slidable in said body closing the mouth of the opening therein, to prevent accidental release of the pin-tongue.

It is found in practice that where the ordinary style of hook-shaped catch is attached to small articles of jewelry which are very delicate in construction such as those provided with enameled faces or the like, that the springing of the pin-tongue out of its natural alignment to carry it into a hook-shaped catch, often twists and breaks or cracks the enamel thereby destroying the beauty of the pin. Then again the ordinary form of safety catch has operating means so small as to be impractical for proper manipulation. To overcome these objectionable features, I have provided an opening in the outer edge of the body of the catch member and have mounted a longitudinally slidable lock bar in this body member, which may be simply pressed by the finger nail of the user on one side to move it to open the mouth of the slot and on the opposite side to close the slot and lock the pin-tongue securely therein.

The invention further consists in the offsetting of one portion of the lock bar thereby providing a yieldable frictional resistance to hold the bar in adjusted position.

With these and other objects in view, the invention consists of certain novel features of construction, as will be more fully described, and particularly pointed out in the appended claims.

In the accompanying drawings:

Figure 1— is a perspective view showing my improved safety catch as mounted in operative position on the back of a thin plate to receive the pointed end of the pin-tongue.

Fig. 2— is a view of the inner face of the

body plate as cut and swaged out of sheet metal.

Fig. 3— shows the plate illustrated in Fig. 2 as folded upon itself the sides being left slightly apart to permit the lock member to be positioned between the folds before being finally closed together.

Fig. 4— shows the sides of the body illustrated in Fig. 3 as having been closed tightly together.

Fig. 5— is a section through the body member on line 5—5 of Fig. 8.

Fig. 6— is an edge view of the lock frame showing the offsetting of one of the arms thereof.

Fig. 7— is a side elevation of the lock frame.

Fig. 8— is a sectional side elevation showing the lock frame mounted in the body member and in unlocked position.

Referring to the drawings, 10 designates the body member which is formed preferably of a plate or strip of sheet metal and when struck up has a rectangular central opening 11 through it and a raised edge 12 formed all around this opening; also its end edges 13 and 14 are raised from the plane of the surface 15 to substantially the same height as that about the center opening.

This plate is then folded at its middle upon itself as illustrated in Fig. 3 leaving the sides 16 slightly apart to permit the lock bar presently described to be positioned therein.

The folding of this plate causes the opening 11 to form a slot 17, see Fig. 8, in the outer edge of the body portion at the fold, for the reception of the pointed end 18 of the pin tongue 19, and the bringing together of the two sides 16 causes the raised portions 12, 13 and 14 to abut, the depressed portions 15 then forming two longitudinal grooves or channels 20 and 21 through this body member for the reception of the lock member 22.

This locking frame or member 22 is preferably formed of thin sheet springy stock cut out into substantially a hollow square having an opening 23 thereinto. One of the legs 24 of this frame is preferably offset out of alignment with the other members of the frame, whereby when this frame is positioned in the body member and the sides 16

- of the latter are closed together the spring of these legs cause a frictional resistance to be exerted on this frame, which serves to retain it in adjusted position whether 5 open or closed and prevent it from moving without being manipulated by the wearer, and the raised portions 12 on the inner faces of the sides serve as stops to limit the movement of the lock in both directions.
- 10 In order to render this lock frame more accessible I have cut away the opposite side edges 25 of the body member so that the finger nail of the user may more readily follow the edge of the frame in moving it either 15 to open or closed position.

The lower or free edges of the folded sides 16 are prevented from spreading when attached to the body of the pin or brooch, which latter is represented by the plate 26 20 which attachment may be made by solder or other convenient means.

By forming the catch member with an opening on its outer edge, there is no necessity of providing the usual fulcrum for 25 the pin-tongue, as it is desirable that when the latter is swung down into this opening that it will remain there until the lock frame is moved sufficiently to cause its arm 27 to close the mouth of the opening 17 30 and so positively prevent the pin stem from disengagement with its keeper until again released.

I have also found in practice that by 35 slightly grooving the underside of this arm 27 at 28, a tension on the pin stem serves to more firmly retain the lock frame in closed position.

Another and important feature in my improved safety catch is that the whole device 40 is swaged up out of sheet stock, no solder being employed in its construction, there-

fore the inherent spring of the hard stock in the lock frame member will cause its offset portion to provide a permanent spring friction.

45

The foregoing description is directed solely toward the construction illustrated, but I desire it to be understood that I reserve the privilege of resorting to all the mechanical changes to which the device is 50 susceptible, the invention being defined and limited only by the terms of the appended claims.

50

I claim:

1. A safety catch comprising a body member formed of a plate folded upon itself to form side walls said folded body being slotted inwardly from its margin, a locking member slidable between the folds of said plate and having an arm adapted to 60 close said slot, and abutting portions raised on the inner surface of said plate to definitely determine the space between said folds in which the locking member slides.

55

2. A safety catch comprising a body member formed of a plate folded upon itself to form side walls said folded body being slotted inwardly from its margin, a locking plate slidably mounted to slide between said folds and provided with an arm 70 adapted to close said marginal slot, the stock between said folds about said slot being raised to provide a stop to limit the sliding movement of said lock, and a portion of said lock plate being offset from the plane 75 of the rest of the plate to frictionally retain the lock in adjusted position.

65

In testimony whereof I affix my signature in presence of a witness.

CHARLES A. GOOZEY.

Witness:

HOWARD E. BARLOW.
